ALFRED L. ATHERTON, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

TEMPERATURE-REGULATING MEANS FOR FILAMENTARY ELECTRODES.

1,406,328.

Specification of Letters Patent. Patented Feb. 14, 1922.

Application filed January 29, 1917. Serial No. 145,239.

To all whom it may concern:

Be it known that I, ALFRED L. ATHERTON, a citizen of the United States, and a resident of Edgewood Park, in the county of Allegheny and State of Pennsylvania, have invented a new and useful Improvement in Temperature-Regulating Means for Filamentary Electrodes, of which the following is a specification.

10 My invention relates to heat-regulating means for filamentary electrodes, such, for example, as the cathodes of hot-cathode converters, and it has for its object to provide apparatus of the character designated whereby an electrode may be maintained at substantially a predetermined temperature, irrespective of changes in the load current flowing thereto.

20 In the accompanying drawings, Fig. 1 is a diagrammatic view of a converter of the hot-cathode type, together with auxiliary heating and load circuits, embodying a preferred form of my invention; and Figs. 2 to 6, inclusive, are diagrammatic views of modifications of the system shown in Fig. 1.

25 It is well known that, if two electrodes be placed in proximity to each other, one electrode being sufficiently hot to emit electrons and the other being comparatively cold, and 30 an alternating electromotive force be impressed across said electrodes, current waves will flow to the hot electrode as a cathode and will not flow in the reverse direction.

The above-noted principle has been quite 35 widely employed in converters for changing alternating currents into direct currents and also for wireless detectors and other analogous uses.

40 In the various embodiments of this principle, the two electrodes are generally placed within a closed container and said container is either highly evacuated or is charged with an inert gas, such, for example, as argon or nitrogen. The cold electrode is generally 45 given the form of a mass of refractory material, such, for example, as tungsten or carbon, and the hot electrode is generally formed, in a filamentary shape, from a similar refractory material. The cathode is 50 maintained at a suitable temperature for starting and operating the device by passing heating current thereto from an auxiliary current source.

It is obvious that, with apparatus of the

character designated, if sufficient heating 55 current from the auxiliary source is initially passed through the filamentary electrode to start the device into operation, the subsequent flow of load current will still further heat said filamentary electrode, leading to 60 the danger of overheating the same. It is, therefore, desirable that the amount of auxiliary heating current be decreased with an increase in the load current so that the filament may be maintained at all times at a 65 substantially uniform temperature, said temperature being sufficiently high to maintain a pronounced electronic emission but not so high as to cause the filamentary electrode to be unduly short-lived.

70 Apparatus to fulfil the above conditions may be developed in a great variety of different forms, as will hereinafter more fully appear.

75 Referring to Fig. 1, a converter is shown at 7, said converter comprising a closed container 8 provided with an anode 9 and with a filamentary cathode 10. Energy for the operation of the converter 7 is supplied from any suitable source, such, for example, as a 80 transformer 11 embodying a primary winding 12, a main secondary winding 13 and an auxiliary secondary winding 14. The three windings 12, 13 and 14 are mounted on a common core 15, the main secondary winding 13 being in relatively close proximity to the primary winding 12, whereas the auxiliary secondary winding 14 is quite widely removed from said primary winding. The two terminals of the main 85 secondary winding 13 are connected, respectively, to the anode 9 and to the cathode 10 through a suitable load device 16. The two terminals of the auxiliary secondary winding 13 are connected, respectively, to the two 90 terminals of the filamentary cathode 10.

95 The operation of the apparatus thus described is as follows. Upon supplying energy to the primary winding 12, an electromotive force is developed in the auxiliary 100 secondary winding 14 which causes current to flow through the filamentary cathode 10, raising the latter to an electron-emitting temperature. When this condition is reached, alternate half waves from the main secondary winding 13 flow from the anode 9 to the cathode 10 and back through the load, establishing the load current of the device.

The load current would tend to still further heat the cathode 10 were it not for the following action. The magnetomotive force of the main secondary winding 13, when traversed by load current, causes an appreciable flux leakage in the transformer 11 between the primary winding 12 and the secondary winding 13. The leakage flux is subtracted from the flux formerly traversing the auxiliary secondary winding 14, and the electromotive force produced in said auxiliary secondary winding is, therefore, decreased, reducing the flow of auxiliary heating current to the filament 10.

10 With a decrease in the load current, the converse action takes place. The reduction in the magnetomotive force of the secondary winding 13 permits an increase in the flux traversing the auxiliary secondary winding 14 and, therefore, increases the heating current supplied to the cathode 10.

15 Referring to Fig. 2 for a modified form of my invention, I show a converter 7, as before, deriving its energy from a transformer 11 provided with windings as described except that the two secondary windings may have an equally close relation to the primary winding. The filamentary cathode 10 may be energized from the secondary winding 14 by closing a suitable switch 17 in its upper position.

20 An auxiliary transformer 18, similar to the ordinary constant-current transformer, is also provided for the energization of the filamentary cathode 10. Said transformer comprises a fixed primary winding 19 which is inserted in the load circuit of the device and a movable secondary member 20 which is counter-weighted, as indicated. The counter-weighting system is such that the device has an inverse ratio, that is to say, an increase in the primary current causes such repulsion of the secondary winding as to actually decrease the secondary circuit, as distinguished from the ordinary constant-current transformer wherein the secondary current remains substantially constant over wide changes in the primary current.

25 Having initiated operation in the apparatus of Fig. 2 by the closure of the switch 17 in its upper position, said switch is thrown to its lower position, whereupon the filament 10 is transferred from the secondary winding 14 of the main transformer to the secondary winding 20 of the auxiliary transformer and thereafter, so long as the apparatus remains in operation, the effect of the auxiliary transformer 18 is to maintain substantially uniform heat in the filament 10, irrespective of changes in the load current.

30 Referring to the form of my invention shown in Fig. 3, the main parts of the system are as before, and an auxiliary current transformer 21 is provided in addition. The primary winding of said auxiliary trans-

former is connected in the load circuit and the secondary winding thereof is connected in the auxiliary heating circuit so that its electromotive force opposes that of the secondary winding 14. Under these conditions, 70 the effect of the transformer 21 is negligible until the flow of load current is initiated, whereupon an electromotive force is produced in the secondary winding thereof which is proportional to the load current 75 and, therefore, tends to neutralize the electromotive force of the winding 14 and to reduce the heating current with an increase in the load current.

35 In the form of my invention shown in 80 Fig. 4, the filamentary cathode is shown deriving its heating current from an auxiliary source of direct current 22, as is frequently the case. Said auxiliary heating current traverses an adjustable resistor 23 85 which is under the control of a solenoid 24 or other electromotor device. The arrangement is such that, when no load current is flowing, the effective value of the resistor 23 is a minimum, permitting the flow of a maximum heating current. As the load current increases, more and more of the resistor 23 is inserted in circuit, and the heating current derived from the battery 22 is reduced in amount, resulting in the desired maintenance of substantially uniform temperature at the cathode 10. If an alternating source be employed for the heating current, such, for example, as an auxiliary secondary winding 90 on the supply transformer, the load-responsive regulating device would preferably take the form of an adjustable reactor rather than the form of an adjustable resistor.

40 Thermostatic means may be employed, if necessary in order to achieve the desired end. A system of this type is shown in Fig. 5 wherein a thermostatic device 26 is mounted in proximity to the container 110 8 of a converter 7, said thermostat being preferably mounted adjacent to the cathode 10. A heating coil 27 surrounds the thermostat 26 and is inserted in a portion of the circuit carrying only load current. A 115 contact member 28 is so mounted that the thermostatic member 26 makes contact therewith when cold. A resistor 29 is normally connected in the circuit of the circuit of the auxiliary heating current so as to be 120 in series with the cathode 10. In operation, at starting, the thermostatic member 26 is cold and rests against the contact member 28, short circuiting the resistor 29 and permitting the flow of a large heating current 125 to the cathode 10. When the thermostat 26 is heated by the joint action of the cathode 10 and of the heating coil 27, contact is broken with the member 28, and the heating current is forced to traverse the 130

resistor 29, thus being radically diminished in amount. Obviously, the thermostat 26 may be caused to depend entirely upon either the container 8 or upon the heating 5 coil 27 as a heating source.

In the form of my invention shown in Fig. 6, a resistor 30 is included in the load circuit and mounted in close proximity to a resistor 31 mounted in the auxiliary heating 10 circuit. The resistor 30 is so proportioned that it varies in temperature with changes in the load current. The resistor 31 is a conductor of the first class and is so proportioned that it is not heated to 15 any great extent by the flow of heating current therethrough. Thus, at the start, the auxiliary heating current traverses the resistor 31 with but little opposition because of the resistance thereof. With the initiation 20 of load current, the resistor 30 becomes hot and transmits heat to the resistor 31 in such amount as to radically increase the resistance thereof, thus cutting down the amount of auxiliary heating current.

25 It is obvious that my invention is susceptible of still further changes and alterations without departing from the spirit thereof and elements shown in certain figures might equally well be employed in systems of certain other of the figures. Furthermore, it is obvious, for example, that, instead of introducing the resistor 29 in series with the filament 10 in the system of Fig. 5, the thermostat 26 might be employed to close 30 a shunt path around said filament, but changes of this character come within the province of the skilled electrician and do not cause systems embodying the same to be patentably distinct from each other.

35 40 While I have shown my invention in a plurality of forms, it is not so limited but is susceptible of various minor changes and modifications without departing from the spirit thereof and I desire, therefore, that 45 only such limitations shall be placed thereupon as are imposed by the prior art or as are indicated in the appended claims.

I claim as my invention:

1. The method of operating a filamentary 50 space-current device, consisting in causing a heating current and a load current to pass through the filament and causing the heating current to decrease when the load current increases, and vice versa, in such manner 55 as to maintain the filament temperature substantially constant.

2. The combination with an electric apparatus embodying a closed tube provided with an anode and a filamentary cathode, of

means for passing a heating current through 60 said cathode, means for passing a load current between said electrodes, and control means for automatically decreasing said heating current in response to an increase in said load current, whereby said filamentary 65 cathode is maintained at substantially a uniform temperature.

3. The combination with an electric apparatus embodying a closed tube provided with an anode and a filamentary cathode, of 70 means for passing a heating current through said cathode, means for passing a load current between said electrodes, and a current-responsive device subject to the action of the load current and operative to inversely 75 adjust the amount of said heating current.

4. The combination with an electric apparatus embodying a closed tube provided with an anode and a filamentary cathode, of 80 means for passing a heating current through said cathode, means for passing a load current between said electrodes, and a current-responsive device subject to the action of the load current and operative to decrease 85 said heating current with an increase in said load current and vice versa.

5. The combination with an electric apparatus embodying a filamentary electrode, of 90 means for feeding both a load current and an auxiliary heating current to said filament and automatic means for adjusting said heating current in an inverse relation with respect to said load current.

6. The combination with an electric apparatus embodying a closed tube provided with 95 an anode and a filamentary cathode, of means for passing a heating current through said cathode; means for passing a load current between said electrodes, said filamentary cathode being heated both by 100 said heating current and by said load current, and means controlled by said load current and automatically operative to regulate said heating current so as to maintain said filamentary cathode at a constant tempera- 105 ture.

7. The method of operating a filamentary rectifier consisting in passing a heating current and a load current through the filament and magnetically controlling the relative amounts of said currents to effect an increase in one as the other decreases and vice versa.

In testimony whereof, I have hereunto 110 subscribed my name this 20th day of January 1917.

ALFRED L. ATHERTON.
